CUTTING DIE MOUNTING AND EJECTOR

Joseph E. McClellan, Oakland, Calif., assignor to
himself and La Verne S. McClellan, Oakland,
Calif., as joint tenants

Application June 10, 1948, Serial No. 32,097

2 Claims. (Cl. 164—33)

1

The invention relates to a die for cutting blank pieces from leather and other homogeneous fibrous sheet materials.

The primary object of the invention is to provide a die set which is operative to effect a clean cutting of fibrous sheet material, and particularly leather.

Another object of the invention is to provide a blanking die set of the character described in which a sheet to be cut is positively gripped before and while the cutting element is applied.

A further object is to provide a die set of the character described which is particularly adapted for its mounting in, and actuation by, a stamping machine having a power-controlled plunger which is reciprocative with respect to a bolster or bed of the machine.

The invention possesses other objects and features of advantage, some of which, with the foregoing, will be set forth or be apparent in the following description thereof, and in the accompanying drawings, in which,

Figure 1 is a side elevation of a machine mounting the die set, the different die assemblies being mutually separated to their limit.

Figure 2 is a plan view of the die set taken at the line 2—2 in Figure 1, portions of the structure being broken away.

Figure 3 is a vertical section of the die set taken at a plane through the line 3—3 of Figure 2, the co-operating die assemblies being separated as in Figure 1.

Figure 4 is an enlarged portion of the showing of Figure 3 adjacent and across a cutting line of the die set.

Figures 5 and 6 show the die assembly sections of Figures 3 and 4 respectively, but with a presser foot device of the male die clamping a work piece against the opposed face of the die block of the female die before cutting of a blank is effected.

Figures 7 and 8 respectively show the die assemblies of Figures 3 and 4 as related at the end of a working stroke of the male die.

By reason of its inherent structure, leather is recognized as one of the most difficult of sheet materials from which to cut blanks, particularly if the leather is of the desired thickness and quality for such elements as glove and shoe-upper parts. Because the homogeneously fibrous nature of leather has heretofore made its die cutting mechanically difficult and uncertain with available dies, the practice of cutting blanks of leather by striking a hand-positioned cutting die having its cutting edge supporting the die upon

10 a sheet of leather placed on a lead or woolen anvil face is still largely followed, even though the method is extremely wasteful of time because the cut-out blanks frequently require hand trimming, and relatively frequent sharpening or replacements of the cutting element and/or the provision of a new anvil face are required. The present die set has been so designed as to eliminate the labor and mechanical difficulties of the aforesaid usual practice, while providing for a machine operation of the cooperative dies of a set in a speedy and effective manner for cutting out blanks from a sheet of leather, or some other material of a similar nature.

15 For purposes of illustration, a die set embodying the features of my invention is shown as operatively associated with a hydraulically operated blanking press 11 having a C-shaped frame 12 providing a clear working space between its upper and lower arms 13 and 14 respectively. At its forward extremity, the upper frame arm 13 mounts a hydraulic cylinder 15 in which a double-acting piston 20 is operative with its piston rod 16 extending into the working space of the 20 frame to variable degrees in accordance with the position of its piston in the cylinder 15, the extending rod portion carrying a cutting die assembly 17. The lower arm 14 of the frame 12 provides a bed-plate or bolster 19 on which the 25 other die assembly 18 of the die set is supported in cooperative relation to the upper die assembly 17 which is suitably held against rotation about the piston axis, or any other upright axis.

As particularly shown, the lower end of the 30 piston rod 16 is reduced to provide a portion 16' extending from a shoulder 16'' and terminating in a reduced threaded portion 16'''. A plate member 21 receives the piston rod portion 16' therethrough and is arranged to constantly engage the rod shoulder 16'', said member comprising an element of a male die assembly which primarily comprises a cutter 22 carried by a block 23 which is in turn fixed to and beneath the plate in unitary association therewith; the member 23 has an interior opening receiving the 35 piston rod portion 16' therethrough, and is unitarily secured to the plate 21 by an appropriate number of screws 24 threadedly engaging the plate, whereby it and the plate 21 comprise a base member for the working die parts. The cutting 40 blade 22 extends peripherally around the block 23, is relatively thin and of uniform thickness, is suitably fixed to the block edge as by screws 25, and is continuous or effectively so, whereby 45 its downwardly extending sharpened cutting edge

22' defines a continuous predetermined line of cutting for the die in accordance with the peripheral outline of the block which is that of a blank to be cut.

It will now be noted that the fixed lower die assembly 18 essentially provides a continuous groove 26 which is arranged to complementarily and closely receive in its upper portion the cutting edge portion 22' of the cutting blade 22 when the upper die assembly 17 is in its fully lowered position. For providing the groove 26, the present lower die assembly 18 comprises a base plate 27 mounting an inner die block member 28 having its periphery defining the inner wall of the groove 26, and an outer die block member 29 encircling the member 28 and having its bore defining the outer wall of the groove 26. The upper faces of the members 27 and 28 are flat and mutually coplanar and cooperatively provide the support face for a work-piece sheet L of leather, or other sheet material to be cut. Preferably, and as shown, the sharpened edge 22' of the cutting blade 22 is bevelled inwardly therearound, and the right-angle edge 29' provided at the top of the bore of the outer die block member 29 comprises and is utilized as a shearing edge in cooperation with the cutting edge 22' of the blade. Bolts 31 extending upwardly through the base member 27 into the members 28 and 29 fix the latter members to the base to provide the groove 26.

To facilitate an appropriate positioning of the inner block member 28 for receiving the bolts 31 which secure it to the base plate 27, the mutually opposed faces of the member and base may be complementarily stepped at their portions within the line of the bolts 31. Also, a groove 27' may extend from the upper face of the base member 27 in registration with the groove 26, the groove 27' providing a receptacle for small particles of the cut material which may descend through the groove 26. The described lower die assembly 18 may have its base 27 fixed to the bed plate 19 of the press in any suitable manner and following its setting to register its groove 26 with the lowered cutting blade 22 of the complementary die assembly 17 which is to coact with it.

Though a downward movement of the cutter 22 against a piece of material L supported beneath it upon the positioned die plate 28-29 and into the groove 26 is designed to effect a shearing cut through the material between the edges 22' and 29' respectively of the cutter 22 and the outer die block 29, it has been found that a clean cutting of fibrous and laterally stretchable material such as leather may not be assured by such an operation of the die set so far described. The aforesaid difficulty has been overcome in the present die set by providing a means for clamping a work piece L against the die plate 28-29, and adjacent the line of cut, before and while the cutter engages the material in cutting and return strokes thereof; the present work-holding means comprises a presser-foot carried by the movable assembly 11 and appropriately cooperative with the fixed assembly 18.

Noting that the cutting blade 22 extends appreciably below the block 23 which mounts it and defines a blade-bounded space of uniform bore extending beyond the lower face of said block as the line of reciprocation of the assembly 17, a member 32 is slidably mounted in said bore and on the reduced piston rod portion 16' for a limited reciprocative guided movement between a normal position in which it extends

beyond the cutting edge 22' to a position in which the cutting edge 22' extends beyond its lower face 32'. The present member 32 is recessed from below to provide a cavity 34 below its hole which receives the piston rod portion 16', and a nut 33 fixedly mounted on the threaded end 16'' of the rod 16 engages the inner end of the recess and functions solely as a radial stop flange to limit a lowering of the member 32 with respect to the overlying blade-carrying block 23.

The member 32 is normally held seated upon the top of the nut 33 by the action of a suitable number of helical compression springs 35 interposed in a line thereof between the member and block; in the present structure, the springs 35 extend from seats upon the top of the member 32 to the bottoms of downwardly-opening sockets 36 provided in the block 23. The screws 24 which fix the block 23 on the base plate 21 extend from the bottoms of the sockets 36 whereby their heads provide the spring seats of the sockets. Noting that the end face 32' of the member 32 is arranged to seat upon the work piece L while the cutter 22 is operatively advanced beyond it, the cavity 34 is deep enough to permit the limiting extension of the cutter beyond the member without engaging the lower piston rod extremity or the nut 33 with the work piece; as particularly shown, an upper portion 32'' of the member 32 in alignment with the cavity 34 is offset upwardly to provide for the desired constant disposal of the piston rod end 16'' and the nut 33 thereon within the cavity. The portion 32' of the member 32 is arranged for its free disposal in a recess 23' extending into the blade-carrying block 23 from its under side whenever the member 32 is displaced upwardly with respect to the block 23; the arrangement is designed to provide a maximum clearance between the fully raised cutting die assembly 17 and the fixed lower die 18, whereby to facilitate the appropriate manual positioning of a work-piece for the operation of the die set against it.

A member 37 receives and is slidable on the cutting blade 22, and is arranged for substantially the same limited reciprocative movement with respect to the blade as the member 32. Bolts 38 extend upwardly from the member 37 and slidably through holes 39 provided in the plate 21, said bolts having their heads 38' disposed above the plate 21 for supporting the member 37 therefrom in limited spaced adjusted relation thereto. A line of helical springs 41 encircles the bolts 38 and said springs having their upper and lower ends respectively seated at the end face of the plate 21 and the bottoms of seat sockets 42 extending into the member 37 at the bolts 38, the arrangement being such that the member 37 is displaceable toward the plate 21 against the joint resistance of the set of springs 41. It is to be noted that the threaded engagement of the bolts 38 in the member 37 permits an adjustment of this member with respect to the corresponding inner member 32 when the members are in their limiting extended positions with respect to the blade 22.

It will now be noted that the lower faces 32' and 37' of the respective members 32 and 37 are flat and are arranged to be normally coplanar, whereby they may simultaneously engage the upper face of a sheet L at the portion to be cut from it as a blank. Since sheets of leather and other materials to be cut may not be of absolutely uniform thickness, it is preferable that the under face of the member 32 be recessed from

its rim portion, as shown, whereby to insure a positive gripping of a sheet L immediately adjacent the cutting line when the member is projected against the sheet. While the faces 32' and 37' engage the top of a work-piece sheet L, a lowering of the unitary cutter assembly 17 is arranged to provide a shearing cut of the material at the edge 29' of the die block 29 by the cutting edge 22' of the blade 22; if the material L is of leather or other homogenous fibrous material, the working application of the cutting blade must be relatively rapid. Noting that the members 32 and 37 are disposable to resiliently grip a sheet L between them and the upper faces of the opposed die block members 28 and 29 respectively, it will be understood that the members 32 and 37 function as mutually independent presser feet within and without the blade 22, and comprise independently operative sections of a presser foot assembly 32-37 which encloses and is guided on the cutting blade 22 for a working projection of the blade beyond the faces 32' and 37' of the respective sections 32 and 37 in working and return strokes while the latter sections clamp a work-piece to the respective die blocks 28 and 29 as a work-holding means.

While I have herein described the disclosed cutting die assembly 17 having presser feet as being cooperative with the fixed die block assembly 18, it will be understood that this assembly may operate with reasonable efficiency against a work-piece placed on a fixed lead or wooden anvil face in lieu of a die block assembly such as that presently provided. It will also be noted that either of the presser feet 32 or 37 may be provided and utilized along, though their joint use will usually be preferred in the cutting of leather and other relatively soft fibrous materials. Also, in an arrangement such as the present cutter die assembly, the springs behind the presser feet 32 and 37 assure a positive and progressively increasing pressure of the feet against a work-piece sheet L as the cutting blade moves through and beyond the sheet for its cutting of a blank therefrom.

Referring now to the actuation of the piston rod 16 to effect working and return strokes of the cutting die assembly 17, means are preferably provided whereby successive cutting cycles may be provided in a semi-automatic manner. As generally indicated in Figure 1, the operating fluid for the piston 20 of the piston rod 16 is arranged to be alternately supplied to and relieved from the upper and lower cylinder ends through pipes or ducts 44 and 45 which are alternatively connected to fluid pressure and return pipes 46 and 47, and the fluid flow is arranged to be controlled by a suitable valve mechanism provided in a casing 48 and controllable in accordance with the setting of a rotary spindle or stem member 51 extending from the casing 48 and mounting control arms 52 and 53 which extend generally horizontally and oppositely in fore-and-aft relation to the machine frame 12. A link 54 extends from the arm 52 to a hinged connection with an intermediate point of a setting lever 55 which extends forwardly along a side of the frame 12 from a pivot 56 at its rear end. A forward end portion 55' of the lever 52 is disposed within ready reach of an operator at the front of the machine, and comprises a pedal in the present instance.

In its forward end, the arm 53 of the control member 51 is provided with an upright opening 53' through which an upright arm portion 57' of an L-shaped valve control or shipper rod 57 extends. A horizontal arm 57'' of the rod 57 is ad-

justably fixed to the piston rod 16 just above the die plate member 21, as by a suitable clamp 58, and the rod portion 57' is reciprocably engaged in an upright guideway provided on the frame 12 at a point below the range of action of the valve control arm 53. To effect its functioning in a manner hereinafter brought out, a stop member 59 is adjustably mounted on the upright shipper rod portion 57' and is arranged to engage the top of the control arm 53 when the rod 57 is sufficiently lowered with respect to the positioned said arm; the rod and piston are normally held fully raised by reason of the connection of the cylinder bottom with the pressure pipe 46 through the control valve and the duct 45. It will be noted that the shipper rod arm 57'' is constantly operative to prevent a rotation of the piston rod, and the die assembly 17 carried by it, whereby the cooperative alignment of the upper and lower die assemblies is maintained.

Figure 1 indicates by the Roman numerals III and V and VII the positions of the piston 20 when the die assembly 17 is in its position of Figures 3 and 5 and 7 respectively. When a work-piece sheet L of material to be cut has been placed in appropriate position upon the lower die assembly 18 while the movable die assembly 17 is in its normal limiting raised position, a depression of the pedal 55' is arranged to rotate the valve stem 49 to set the control valve for supplying liquid from the supply pipe 46 to the top of the cylinder while connecting the lower cylinder portion with the return pipe 47 for effecting the lowering of the die assembly 17 toward the work-piece L to finally engage the bottom faces of the presser-foot sections 32 and 37 with the work-piece, after which a continued lowering of the piston rod under the liquid pressure is operative to effect a cutting projection of the blade 22 beyond the presser feet and through and beyond the work-piece.

As the die assembly 17 approaches its limiting lowered position, the valve control arm 53 is moved toward its normal position by reason of the engagement of the shipper rod block 59 therewith, and when the arm reaches said position, the liquid connections for the top and bottom of the cylinder are automatically restored to their initial conditions for a repetition of the cutting application of the die assembly 17 the next time the pedal 55' is depressed. The control-valve functioning is preferably such that the movement of the cutter assembly 17 to engage its presser foot parts 32 and 37 with a sheet L is relatively slow, the subsequent working projection of the cutter beyond the presser foot is relatively rapid to provide a "snap" severing of a blank from the sheet, and the final automatic return-stroke lifting of the die assembly to its normal raised position is preferably relatively fast to minimize the time required between operative cycles.

It will now be noted that the present die sets 17-18 are formed and cooperative to cut out a thumb-piece blank for a glove, and that correspondingly constructed die sets may be provided for cutting out the other blanks for the glove. Since the provision of different blanks for use in the assemblies of gloves and shoe uppers requires the use of different die sets 17-18 for providing the required different blanks, it will be noted that the present machine 11 is particularly adapted for the ready successive mounting thereon of the required different die sets, whereby it may serve for the production of all needed blanks of a set. Also, since leather is usually provided in pieces having the outline of a cured

hide, the clearance between the normally separated die assemblies in this machine must be sufficient to facilitate a manual positioning and repositioning of the work sheet for cutting of a plurality of blanks from it.

From the foregoing description taken in connection with the accompanying drawings, the features and advantages of the present cutting die and its operative application will be readily understood by those skilled in the art to which the invention appertains. While I have shown and described a structure which I now consider to comprise a preferred embodiment of my invention, I desire to have it understood that the showings are primarily illustrative, and that such changes and developments may be made, when desired, as fall within the scope of the following claims.

I claim:

1. In a machine for cutting blanks from work-pieces of fibrous sheet material, a support member carried by the machine for its axial reciprocation toward and from the workpiece and comprising a rod mounting a nut at an end thereof and providing a shoulder opposite said nut in spaced facing relation thereto, and a cutting die comprising a base member intermediately and slidably receiving the rod portion between the shoulder and nut and normally seated against the shoulder, a continuous cutting blade extending fixedly from said base member, a presser-foot member having a forward face for engaging the opposed face of a work-piece and normally having its forward face disposed beyond the blade edge, said presser-foot member being reciprocable within the blade-bounded space of the blade and slidably receiving the rod portion between the base member and the nut and being displaceable along said rod portion toward the base member to a limiting position in which it contacts the base member and being provided with a recess extending inwardly from its forward face for constantly and freely receiving the nut, and means yieldingly urging a mutual separation of the base and presser-foot members to a limit imposed by the shoulder and stop of the rod.

20

tual separation of the base and presser-foot members to a limit imposed by the shoulder and nut of the rod.

2. In a machine for transversely cutting blanks from a work-piece of sheet material, a support member carried by the machine for its axial reciprocation toward and from the workpiece and comprising a rod providing a radial stop at an end thereof and providing a shoulder opposite said stop in spaced facing relation thereto, and a cutting die comprising a base member intermediately and slidably receiving the rod portion between the shoulder and stop and normally seated against the shoulder, a cutting blade extending fixedly from said base member, a presser-foot member having a forward face for engaging the opposed face of a work-piece and normally having its forward face disposed beyond the blade edge, said presser-foot member being reciprocable with respect to the blade and slidably receiving the rod portion between the base member and the stop at the rod end and being movable along said rod portion toward the base member and being provided with a recess extending inwardly from its forward face for constantly and freely receiving the stop, and means yieldingly urging a mutual separation of the base and presser-foot members to a limit imposed by the shoulder and stop of the rod.

JOSEPH E. McCLELLAN.
